LADLE CAR

Walter de Fries, Wilkinsburg, Pa., assignor to
 Pittsburgh Steel Foundry Corporation, Glassport, Pa., a corporation of Pennsylvania

Application August 30, 1932, Serial No. 631,003

5 Claims. (Cl. 266—39)

My invention pertains to containers for fluids, particularly in the transportation thereof, and relates, more specifically, to what are known as "ladle-cars" for molten metal,—i. e., cars embodying heat-retaining ladles used not only for the transportation of the metal but also for the storage of the metal for extended periods between transportation.

To serve their double purpose the ladles of such cars must be constructed so as to have a large metal holding capacity (often eighty tons or more) in order that the ratio of the surface of the ladle to its cubical contents be kept as low as is practicable, so that the heat radiation from the shell of the ladle be minimized, thereby extending the period for which the filled ladle can be stored without danger of its load freezing or solidifying.

Although, for the foregoing and other reasons, the ladle of the car should be of large capacity, there exist limitations upon the maximum width, height and length of the car. These limitations originate from existing plant and track conditions. The width of the car is, of course, limited by the gauge of the track upon which it is used, and by the clearance between such tracks, also by the width of the doorways of buildings which the car is required to enter. The height of the car is limited by the distance, above track level, of the runners of the blast furnaces from which the ladle car is required to receive its load of metal, under which runners the car must be placed. Height is also limited by the doorways, bridges, etc., under which the car is required to pass. The length of the car is necessarily limited, since otherwise its center portion would pass beyond the available track clearance in the passing of the car around curves. Undue length of the car, moreover, would involve a correspondingly increased length of the blast furnace runners, which, because of the downward slope necessary to such runners, would place the outer parts of the runners unduly low, and would consequently unduly limit the height of cars required to pass beneath such outer parts. Again, where ladles are demountably supported on their cars and equipped with lifting trunnions for their removal from the car body in loaded or unloaded condition, the trunnion center distance, which is dependent on the ladle length, cannot be too great if the cost of overhead handling facilities is not to exceed economic limitations. Still again, the heavy loads to be carried by such ladles forbid that the length of the ladle be too great because the load would dictate a shell construction so heavy that the

total weight of the car would adversely affect the net loading capacity of the car as a unit.

Ladle cars as now constructed usually follow one of two designs, distinguished by the employment or non-employment of car sills for connecting the end frames of the car proper. Where the periodical removal of the ladle from the car is not required, as in the case of ladle cars with their own integral discharge or dumping mechanism, the ladle is frequently developed in sufficient strength to act not only as the load carrier, but also to withstand stresses incidental to train operation, such as coupler thrusts, etc. Car sills are omitted with this design, which favors a Zeppelin or cigar-shaped container for carrying the hot metal, as best suited for the combined function above outlined. With cars of this character, repouring of the metal through transfer ladles is usually resorted to for delivery of the hot metal to open hearth furnaces and converters for further processing, or to mixers for storage. It is preferable, however, to avoid such repouring operations, with their resultant losses of metal from spilling or skulling. Recent ladle car designs, therefore, feature demountable hot-metal containers of large capacity which are supported on cars built with sills connecting the end frames, to make the cars self-contained for resisting all stresses incidental to load-carrying or train operation. With this type of ladle car the ladle may be filled at the metal producing point and transported to any metal consuming station, there to be lifted from the car and held on stationary supports for future disposition. Another empty container may then be placed on the car, thus releasing the latter immediately for further service.

Safety of operation of such cars and ladles demands, of course, that any possibility of accidental spilling of molten metal be guarded against under all operating conditions. This requirement dictates location of all supports or trunnions of the ladle, whether for car mounting or crane lifting, at an elevation substantially above the center of gravity of the ladle proper when the latter is in normal position. For crane lifting usually two main-trunnions are attached to the ladle at its opposite ends in a plane passing vertically through the longitudinal axis of the ladle. For resting on the car usually two additional trunnions are provided at each end of the ladle, all located in the same horizontal plane, but at equal distances from the center axis, in such a way that any two opposite trunnions may act as turning points for tipping the ladle on the car to permit discharge of its contents to

60

65

70

75

80

90

95

100

105

110

either side of the track. The sidewise disposition of these four trunnions from the center axis is governed by several requirements. One of these requirements is that the trunnions be located outwardly beyond the position of the center of gravity of the empty ladle in its extreme tipped position, so as to avoid any over-turning tendency. Another requirement is that the trunnions be disposed in such a way that the path of travel 10 of the ladle spout during the tipping operation forms as flat an arc as possible with relation to the vertical plane passing through the longitudinal axis of the ladle. In addition, it is desirable to keep the center of gravity of the ladle, 15 whatever its position or the amount of its contents may be, within the limitations of the gauge of the track on which the car travels, to avoid the creation of an over-turning moment for the entire unit of ladle and car combined, particularly 20 on banked curves or other deviations of the track from a truly level condition. These considerations impose limitations, not only on the position of the four tipping trunnions, but on the location of the center of gravity of the ladle, 25 as well as of that of the combined unit (car and ladle). Since the location of the center of gravity of the ladle is largely governed by its shape, and the disposition of its contents therein, the successful design of the entire unit depends to a 30 considerable extent on the proper shaping of the ladle shell.

According to a prior invention, which forms the subject of my copending application Serial No. 559,188, filed August 25, 1931, I have obtained a 35 closed top ladle of relatively large metal holding capacity, which meets the clearance limitations encountered in existing plants by building and track conditions. Such ladle is of the general character disclosed by Patent No. 1,535,482 to 40 Fred E. Kling, having vertical walls which permit easy variation of capacity by changing the height of such walls. According to my said prior invention, however, the shape of the ladle in horizontal cross-section is, as it were, flattened, 45 from the true circle of the prior Kling ladle, into an oval, whereby the interior capacity of the ladle is considerably increased, while retaining at the same time the advantages of the Kling ladle, as to ready availability for different heights, 50 etc.

However, the curved vertical-sided construction characteristic of the ladle of my said prior invention, and of the said Kling ladle, imposes 55 certain limitations on its operation, particularly in connection with tilting. For example, if the bottom section of the ladle extends downward between the side sills of the car far enough to utilize fully available space in that region, clearance does not exist that would permit the passage 60 past such side sills of lifting lugs or the like adapted to receive the hooks of a crane to be employed for tilting the ladle, and it then becomes necessary to provide special tilting means on the car, which in turn prevents the convenient lifting of 65 the ladle off the car. On the other hand, if crane-lugs (such as the lugs 21 of the Kling patent) are provided, and given the clearance from the side sills required to permit tilting of the ladle, the ladle must be carried higher on the car than 70 will permit full utilization of the space between the side sills of the latter. This results in a higher center of gravity for the entire unit, which, as previously stated, is objectionable from a safety viewpoint. Moreover, the carrying of the ladle 75 higher on the car may not be possible within the

same ladle capacity, because of the height limitations above referred to.

Furthermore, it is essential that, in pouring, the pouring lip of the spout be inclined at an angle of 12° or more with respect to a horizontal plane in order to effect proper discharge of the contents of the ladle. This requires a tilting of a ladle with vertical-sided walls through a minimum arc of 90° plus 12°, or 102°. Such tipping range dictates in turn either the location of the four supporting trunnions near the top of the straight-sided ladle portion, resulting in high pouring with objectionable splashing of metal, or else the introduction of four additional auxiliary trunnions, at quite some distance from the longitudinal center axis of the ladle, in such manner that the weight of the ladle shifts, in tilting, from one pair of trunnions to the other and the center of gravity of the ladle and its contents is always kept inward of the trunnions which, at the moment, carry the weight of the ladle. The attachment of such auxiliary, or outside, trunnions to straight-sided ladles of circular or oval shape in horizontal cross-section, requires that the trunnions be of considerable length. They are consequently subjected to high bending moments, and must be of a correspondingly heavy design, which increases the dead weight of the ladle requiring to be lifted, and reduces the loading capacity of any car which is limited to a fixed 105 axle capacity or wheel load on account of track conditions.

An important object of my present invention is to provide a car for the transportation of liquids, such as a ladle car, the container, or ladle, of 110 which has a holding capacity in excess of that obtainable with prior constructions within corresponding dimensions of height, width and depth. Another object is the reduction of the arc through which the ladle has to be tipped for 115 discharge of its contents, irrespective of whether such tipping is done on the car by means of an overhead crane or by other devices provided therefor perhaps on the car itself or on the ground adjacent to the pouring station, or while the ladle 120 is suspended from an overhead crane. Such reduction in the tipping range increases the safety of operation of the entire unit by guarding against overturning either of the ladle or the 125 ladle and car combined. Other objects of my invention, and advantages secured thereby, will appear from the following specification and claims.

I obtain the above objects largely by patterning the ladle of the ladle-car after the characteristic shape of stationary hot-metal storage vessels or "mixers", as they are called, combining sections of several typical designs to form a vessel which lends itself to the solution of all the problems involved. A typical shape employed in stationary mixers is the "barrel-shape", which is a shape defined by at least two radii struck from axes substantially at right angles to each other, as distinguished from a shape of the cylinder or sphere type, which is defined by but a single axis. 130 The lower portion of my ladle shell is of almost semi-barrel shape, being mounted in such a way that the axis of the barrel follows the center line of the track and the barrel heads form the ends of the ladle. The middle portion of my 135 ladle is an inverted frustum of a four-sided pyramid with a substantially rectangular base. The longitudinal sides of such middle portion are slightly bowed, to coincide with the barrel-shaped bottom at their lines of junction, and 140

80

with the curve of another barrel segment, which forms the top enclosure of my container. The joint between the bottom and the middle portion is made on straight tangential lines to provide smooth flow-lines for the contents, while that between the middle and upper or roof portion is made in angular fashion, similar to the joint between the barrel body and barrel heads, which latter form the end closures for my container. Thus the container, from the bottom up to the intersection of the middle portion and roof portion, is of substantially parabolic shape in vertical cross-section. This type of container is characterized by an interior space of constantly increasing cross-sectional area in any horizontal plane above its bottom and up to the roof joint, as distinguished from the uniform cross-sectional area in successive longitudinal planes above or below the supporting axis typical of such ladies as that of the before-mentioned Kling patent and my said copending application, and, further, as distinguished from a cross-section of decreasing area above the horizontal axial plane typical of any container represented by a figure of revolution about a horizontal axis, such as that disclosed by Patent No. 1,251,282 granted to J. D. Pugh.

In place of charging hoppers and nose type spouts however, which feature stationary mixer installations, I provide openings in the roof adjacent to the side walls, flaring outwardly as they rise, and forming with their built up lips substantially extensions of the side walls above the intersecting roof-line. Such inclination of both side-walls and the extensions thereof constituted by the spout-lips reduces the tilting movement necessary to empty the ladle and provides such clearance between the bottom portion of the metal ladle and the side-sills of the car proper as permits the installation of lifting lugs properly located for convenient engagement and disengagement by crane hooks, while still usefully employing the space available between the car side sills.

I have described, by way of example, in the following specification, and shown in the accompanying drawings, one form of ladle car embodying my invention, but I wish it to be understood that the invention may be embodied in other forms, and that changes may be made in the form described and shown, without exceeding the scope thereof, as defined in the appended claims.

In the drawings, Fig. 1 is a plan view of the ladle car; Fig. 2 is a side elevation as viewed from the lower side, Fig. 1; Fig. 3 is an enlarged end elevation thereof as viewed from the right of Figs. 1 and 2; and Fig. 4 is an enlarged vertical section taken on line IV-IV of Fig. 2.

Referring now to the drawings, the ladle car therein selected for illustration is of a large type, embodying four four-wheel trucks 13 each two of which are interconnected by a longitudinal bolster with integral car end-frame 12, adapted to receive draft gear assemblies, safety chains, air and hand-brake equipment and other standard appliances required for safe train-operation. The car end-frames 12 support a cradle 10 pivoted, at 11, centrally of the end frames and having two or more side bearings at each end, through which the entire weight of the car and load is transmitted to the trucks 13 operating on tracks 13a. The cradle 10 comprises a pair of side sills 14 with depressed center sections, between which the bottom of the ladle is slung,

and is provided with cross-connecting members 15 and 15a between the two side sills 14, each having two suitable bearings 16 for receiving the four supporting trunnions carried by the ladle. The foregoing construction permits of the entire cradle being constituted by a single casting, which, in turn, permits the metal used for such casting to be an alloy steel having high strength characteristics. Thus, for the required strength, the cradle may be lighter than would be possible with the grade of steel available for producing a welded or otherwise built-up cradle.

The ladle is of suitably reinforced cast steel and plate construction, provided with an interior lining of refractory material. It consists of a pair of vertically inclined side walls 17, with the centers of their upper ends spaced apart by a distance equal to that between the outside faces of side sills 14, so as to take advantage at this point of the full width, governed by side clearance limitations for the car. These side walls are bowed, as shown in Fig. 1, to suit the curvature of the barrel sections 18 and 22 forming top and bottom of the container, the degree of curvature being just sufficient to permit effective keying of the brick shapes between the supporting end walls. When the ladle is tilted by 90° or more for discharge of its contents, one side wall or the other replaces the roof as the top-most portion of the container and its refractory lining, weakened perhaps by erosion, would tend to fall into the metal, were it not properly keyed as required for regular arch construction. Hence, the vertically inclined side walls are curved to a degree sufficient to permit keying of a brick-lining applied to their inside in self-supporting arch-construction supported by the lining of the ends.

The inclination of the side walls 17 is such that they approach each other in a downward direction, as is easily seen by comparison with the strictly vertical chain lines "a" shown for the purpose on Fig. 4 of the drawings. The lower edges of the side walls join the barrel-shaped bottom section 18 tangentially, so as to avoid lateral stresses and to secure a continuity of inside surface which is conductive to an easy and convenient flow of the contents from the ladle. The barrel-type construction of the bottom section, 18, is resorted to as a shape which is self-sustaining under the load it has to carry, when the ladle is in its normal position. It eliminates the requirement for stiffening ribs or beams, which would have to be added to a straight cylindrical bottom, for instance, to give it adequate strength. Such additional stiffening members would occupy space which, with the barrel-shaped construction of bottom section, is utilized for increasing the cubical capacity of the container. Moreover, the barrel-shaped construction of bottom section lends itself particularly well to the mounting of the ladle on the car in such a way that its lowest point is substantially level with the undersides of the side sills 14 of the cradle, or in other words, is as low as is consistent with the minimum required vertical track clearance. The result of such mounting of the ladle with its bottom dropping in between the side sills to a maximum extent is a minimum over-all height of the entire unit (car and ladle) for any given capacity, or, if the height chosen is the greatest allowable, a maximum cubical capacity of the ladle for that height. Another advantage of the barrel-shaped bottom originates from the fact that the decrease in transverse bottom radius, starting from the mid-

80

de of the ladle and continuing towards either end, provides, in conjunction with the sloping side walls, space between the outside of the bottom and the insides of the side sills which gives 5 clearance for the movement of lifting lugs past the side sills of the car when the ladle is tilted, and thus permits such lifting lugs to be employed.

A pair of such lifting lugs, designated 19 and 10 carrying pins 20 for engagement by crane-hooks or the like, are mounted on each side of the bottom section 18 in such a manner that they do not extend past the outside surface of the side sills, or, in other words, that they stay within the 15 side clearance limitation for the car. The lugs are placed relatively low,—so that the lifting effort, for tilting the ladle, may be in an approximately vertical direction, but high enough to provide sufficient clearance between the top plate 20 of the side sill and the under side of the lug or pin for the easy entry or disengagement of the crane hook or the like. It will be seen from the chain lines "b" which have been placed on Fig. 4 to show the path taken by the outside edges 25 of the lugs during the tilting operation that when the ladle is tilted by crane-hooks or the like attached to one pair of lugs, the other pair of lugs will clear the car sill past which they must move during such tilting operation. The provision 30 of a pair of lifting lugs on each side of the ladle, instead of the single lug which is usually mounted in the middle between the trunnions, not only avoids concentration of stresses, originating from the tipping operation, on the middle portion 35 of the ladle, already burdened by a maximum of load stresses due to its beam action, but also halves the load each crane-hook or the like has to carry, so that their dimensions may be smaller, with correspondingly less clearance requirements. 40

The employment of two lifting lugs on each side of the car, and the construction of ladle which permits such employment, with the requisite clearances, is of material importance. Where 45 single lugs are employed for ladles of large capacity, their size, and that of the hooks engaging them, becomes such that the lugs must extend a considerable distance outwardly from the ladle proper. Since their outermost parts 50 must be within the permissible transverse track clearance, this correspondingly reduces the width of the ladle and therefore its capacity. My construction of ladle, permitting the employment of two pairs of lugs in the manner just explained, 55 avoids this.

The upper edges of the inclined side walls 17 are held in spaced relationship by the roof section 22 of the ladle. In contrast with the almost semi-barrel shape in which the bottom section 60 18 is constructed, the roof section 22 is constructed in the shape of a comparatively shallow segment of a barrel, with its axis again following the track center line. This gives substantially straight horizontal joint lines between the side 65 walls and the roof section which are highly convenient from a construction standpoint. Since the roof, like all other portions of the ladle, has to be lined with refractory material it follows that it is highly desirable that the lining be arched 70 in order to be self-supporting under all operating conditions. The depth of such arching is governed by the span between supports, with short spans requiring the least depth. It follows, therefore, that if roof arches are thrown across the 75 longitudinal axis of the ladle less curvature will

be required than if the arches are thrown in the direction of the longitudinal axis of the container, and I construct the roof section 22 of my ladle in the former manner.

Every inch of decrease in roof curvature permits corresponding increase in side wall height, with resulting increased ladle capacity for a fixed overall height of the container. Therefore the arching of the roof section across the shorter distance between ladle walls permits full utilization of available space for loading purposes. The use of comparatively large radii for the shallow arches of the roof-section results in an almost rectangular intersection between roof section and side walls, as distinguished from the tangential junction of the side walls with the bottom section, 18.

For filling or emptying the ladle I provide two openings 23 and 23a, in the roof adjacent to the side walls and midway between the trunnion-supporting ends of the ladle. These openings are adapted to be closed by covers 27 disposed so as to meet in edge-to-edge relation when closed. Each cover is mounted on an arm 28 pivoted to the roof so that the cover occupies a horizontal plane, the arms being provided with wheels 29 adapted to travel on arcuate tracks 30 carried by the roof. The arms are geared together as indicated at 31, so that movement of one cover, either by hand or by an appropriate moving device, will effect 105 a corresponding movement of the other. It will be observed that the covers, as thus constructed do not, whether open or closed, occupy space above the center of the roof of the ladle.

The openings are developed into spouts in the 110 manner indicated on the drawings, with the pouring lips of such spouts forming continuations of the side walls to insure a straight flow line, free from pockets. Disposition of the spouts in this manner insures free flow of the contents of the 115 ladle from every direction, so that a ladle of this type may properly be termed "self draining," with the least angularity of revolution around its turning axis.

The construction of the end walls of the ladle 120 departs entirely from past practice in the construction of ladle cars. In place of cylindrical end portions forming a continuation of the side walls, I provide substantially flat end walls 21 disposed at right angles with the longitudinal axis 125 of the ladle, thus closing the hollow structure formed by the other members of the ladle, heretofore described. These end walls 21 form the "heads" for the barrel-shaped bottom and roof sections and extend between them in a straight-line connection to the side-walls. For lining purpose, I again prefer to "dish" such heads just sufficiently to permit keying of their brick lining, so as to better secure the lining against shocks and thrust impacts resulting from the car movement and switching. While these walls, in normal operation of the ladle, do not assume a position in which the bricks would naturally tend to drop therefrom, a slight outward bowing in dome fashion to a high point will readily provide for 135 the lining being locked in position, without calling for that degree of curvature, which would make it self-supporting under suspended conditions.

The end walls 21 of my ladle carry trunnions, 140 designated 25 and 25a on the drawings, and adapted to rest in the trunnion bearings 16 of the transverse members 15 and 15a of the cradle. Forward of these trunnions, and with shoulders disposed outwardly beyond their ends, are provided crane- 145

Lifting trunnions 26, one at each end of the ladle, said trunnions being attached in the vertical center of the ladle-ends in a plane usually above that of the location for the other trunnions, so as to provide adequate clearance between their undersides and the top surface of the cradle 10 for entry or exit of crane-hooks or other lifting devices. By these means the ladle may be handled from and to the car either empty or filled with metal, and can be made to discharge its contents by turning around the common axis of the trunnions 26. For pouring of metal from the car, the ladle rotates about the common axis of trunnions 25 or 25a, depending upon which side of the track the discharge is to take place, the metal flowing through the spout, 23 or 23a, nearest to the turning axis. For turning the ladle, crane-hooks or other lifting devices are connected with the pins 20 of that pair of lifting lugs 19 which are on the side of the ladle opposite to that at which the pouring is to occur, and are then gradually raised to effect the pouring operation. The chain line "C" placed on Fig. 4 shows the path of the lip of the spout 23 as the ladle is turned around the common axis of trunnions 25, beginning with the full line position and terminating in the dotted line position where the spout lip has the required minimum inclination of 12° with any horizontal plane to secure full drainage of the metal from the ladle, although the latter has turned through an arc of only about 90° plus 6°, the increased bevel having been obtained by corresponding inclination of the side walls of the ladle. The algebraic expression for this postulate is, that the angle x equals the sum of the angles y and z (Fig. 4).

It is evident that the center of gravity of the ladle, normally situated in the common vertical plane passing through the longitudinal axis of the container and the track center line, does not move as far towards the side of the car with this restricted tipping motion as would be required with a ladle having vertical side walls. Consequently I can situate each pair of supporting trunnions in a position at once favorable from the two standpoints of lifting efficiency and pouring characteristics, and can obtain safety of operation without having to resort to auxiliary pairs of trunnions, usually employed in succession.

The path followed by the center of gravity of the ladle during the tilting of the latter in the empty state is shown by the chain line "e" upon Figure 4 of the drawings, G designating the position of the center of gravity of the empty ladle when in upright position, and G' designating the position of the same gravity-center when the ladle is in its dotted line position. When the full ladle is tilted for pouring, it will be substantially empty by the time it reaches the dotted line position of Fig. 4, and its center of gravity will therefore be at G'. It will be noted that with the ladle in the final discharge position its center of gravity, G', is well back of the vertical plane extending through the axis of the trunnion 25, so that there is no tendency towards overturning of the ladle, and ample moment is available to secure the automatic return of the ladle into normal position on the car when the lifting lugs are lowered again. As chain line "d" in Fig. 4 further indicates, the center of gravity of the tilted container has not passed beyond the nearest rail of track 13a, so that, even should there be a connection between the ladle and the car, such as might cause them to swing or rock in unison upon sufficient transverse force being applied, there is no tendency

towards upsetting of the entire unit from the track. This is due to the entire absence of any overturning moment originating from any position which may be assumed by the ladle on the car.

Summarizing the various construction characteristics heretofore outlined, it may be stated that my ladle car has a considerably greater capacity with less dead weight, for a given length, height and width, than has heretofore been obtainable. This is largely due to my application to ladle-cars of a number of the features which characterize stationary mixers,—such as, for instance, the substantially flat end walls, producing a box-shaped middle section of the ladle, and the employment of a barrel-shaped bottom. The embodiment of these features in the ladle of a ladle-car not only simplifies the design, but makes the pouring operation easier and safer and avoids the necessity of resorting to more than a single pair of trunnions on each end of the ladle. An additional advantage of my ladle, resulting from the construction employing inclined side-walls in combination with a barrel-shaped bottom, is the opportunity for mounting lifting lugs in pairs on each side of the ladle without sacrifice of space for loading purposes yet conveniently accessible for engagement with tipping devices not mounted on the car. The absence of a special mechanism for tilting the ladle when on the car eliminates any necessity for more or less fixed connections between car and ladle, so that the latter may freely be removed, giving greater flexibility in metal handling without repouring and permitting more frequent use of the car proper for transportation purposes.

I claim:

1. A container for fluids, comprising a bottom portion and a roof portion each shaped in the form of a barrel section, side portions connecting said bottom and roof portions and inclined away from each other from said bottom portion to said roof portion, substantially flat end portions disposed at right angles with the longitudinal axis of the container and connecting the ends of said side portions and closing the ends of said bottom portion and roof portion, and a trunnion mounted on each of said end portions above the center of gravity of the filled container.

2. A container for fluids, comprising a bottom portion and a roof portion each shaped in the form of a barrel section, side portions connecting said bottom and roof portions and inclined away from each other from said bottom portion to said roof portion, substantially flat end portions disposed at right angles with the longitudinal axis of the container and connecting the ends of said side portions and closing the ends of said bottom portion and roof portion, and a pair of trunnions mounted on each end portion, one on each side of the longitudinal center line of the container, said trunnions being disposed above the center of gravity of the filled container.

3. A container for fluids, comprising a bottom portion shaped in the form of a barrel section, side portions connected with said bottom portion and extending upward therefrom in an outwardly inclined direction, substantially flat end portions connecting the ends of said side portions and closing the end of said bottom portion, a roof portion shaped in the form of a barrel section and connecting with said side portions, said roof portion being formed with an opening adjacent one of said side portions, and said side portion extending past its intersection with said roof portion

at said opening to form a spout lip, and supporting members one mounted on each of said end portions at a level above that of the center of gravity of the filled container.

- 5 4. A container for fluids, comprising a bottom portion shaped in the form of a barrel section, side portions connected with said bottom portion and extending upward therefrom in an outwardly inclined direction, substantially flat end portions 10 connecting the ends of said side portions and closing the end of said bottom portion, a roof portion shaped in the form of a barrel section and connecting with said side portions, said roof portion being formed with an opening adjacent 15 one of said side portions, and said side portion extending past its intersection with said roof portion at said opening to form a spout lip, and a pair of trunnions mounted on each of said end portions at a level above that of the center of 20 gravity of the filled container, the trunnions of each pair being disposed on each side of the longitudinal axis of the container.

5. A ladle car comprising in combination a

pair of car trucks, a truck frame provided with side sills mounted on said trucks and curved downwardly therebetween, a closed ladle provided with a bottom having the shape of a barrel section and a width adapted to fit between and rest below said side sills, a top of the same general shape as said bottom but of lesser curvature and a width substantially equal to the outside width of said car frame, side sections joining said bottom and top together and end walls therefor disposed substantially at right angles to the axes of the ladle, trunnions on said end walls for rotating the ladle to discharge its contents from openings located in said top adjacent the edge of said top and bottom joining sections, said trunnions being disposed above the center of gravity of said ladle and supports mounted on said frame for engaging said trunnions, said supports being so located as to permit the ladle to be rotated so as to discharge its contents from said openings over the edge of said side sills with a minimum lifting of the ladle.

WALTER DE FRIES.
